UNITED STATES PATENT OFFICE.

OLUF TYBERG, OF NEW YORK, N. Y., ASSIGNOR TO RUFUS L. PATTERSON AND GEORGE ARENTS, JR., OF NEW YORK, N. Y.

WRAPPING-MACHINE.

SPECIFICATION forming part of Letters Patent No. 729,454, dated May 26, 1903.

Application filed October 6, 1902. Serial No. 126,054. (No model.)

To all whom it may concern:

Be it known that I, OLUF TYBERG, a citizen of the United States, residing in New York, county of Kings, and State of New York, have 5 invented certain new and useful Improvements in Wrapping-Machines, fully described and represented in the following specification and the accompanying drawings, forming a part of the same.

This invention relates to certain improvements in wrapping-machines, and has for one of its objects to produce an improved form of wrapping mechanism for wrapping cigars or similar articles which will be simple in construction and efficient in its operation.

A further object of the invention is to produce an improved wrapping-machine in which the wrapper shall be taken by the wrapper-presenting devices as it is cut, said presenting devices coöperating with and forming a part of the cutting devices and thereafter operating to present the wrapper to the wrapping mechanism.

A further object of the invention is to produce an improved wrapper-cutting mechanism.

With these and other objects in view the invention consists in certain constructions and in certain parts, improvements, and combinations as will be hereinafter fully described and then specifically pointed out in the claims hereunto appended.

In the accompanying drawings, Figure 1 is a side elevation, partly in section, of a form 35 of mechanism embodying the invention. Fig. 2 is a front elevation, partly in section, of the construction illustrated in Fig. 1. Fig. 3 is a plan view of the construction shown in Fig. 1. Fig. 4 is a detail sectional elevation of the 40 cutting-die and its bed, and Figs. 5, 6, and 7 are diagrammatic views.

Referring to the drawings which illustrate a concrete embodiment of the invention, 1 indicates the frame, which may be of any 45 suitable configuration. In the construction shown the wrapper which is to be presented to the wrapping mechanism hereinafter described is cut in the machine by a die and a coöperating member, and in the preferred 50 form of the construction the leaf or sheet material from which the wrapper is cut will be

retained in position with respect to the die by suction, though other retaining devices might be employed. As shown, the frame of the machine is provided with a chamber 2, 55 with which communicates a pipe 3, leading to a blower or any other convenient suction-producing means. The top of the chamber is formed by a perforated plate 4, upon which rests a box or table 5, said box or table forming a chamber which is in communication with the suction-chamber 2 through the perforations in plate 4. This box or table has an opening in its top in which the cutting-die 6 is located, said die in the present machine 60 being shown as a closed die and of a configuration suitable to form a wrapper for a cigar. The die is arranged to fit loosely in the opening in the table 5, so as to leave a space 7, through which the suction acts to hold a leaf 70 on the table.

In cutting thin sheets of material by means of dies which have two opposite sides difficulty is frequently experienced in obtaining a clean cut, for the reason that the two sides 75 of the die may not be ground to lie exactly in the same plane or for the reason that the face of the coöperating cutting member may not always lie in a single plane. In the preferred form of the construction, therefore, 80 the die will be arranged so that while it is positively supported it will be capacitated to tilt in order to compensate for any inequalities. The construction of the die to effect the function or purpose referred to may be varied 85 within wide limits. As shown, the base 8, which carries the die and with which the die is shown as integral, is cut away, as indicated at 9, so as to form a knife-edge bearing, upon which the base and die are pivoted. While 90 this knife-edge bearing constitutes a preferred form of construction, it is possible to employ other forms of pivotal supports for the die which will permit the desired tilting movement. When the term "pivotal," therefore, is herein used, it is to be construed as covering any form of positive support upon which the die is permitted to rock.

In order to keep the die from shifting its position, it is or may be provided with a segmental bearing, (indicated in dotted lines at 10 in Fig. 4,) said bearing engaging with a

small box 11, also shown in dotted lines in this figure.

The cutting member which co-operates with the die may be of any suitable description.

5 Preferably, however, it will be a roller, and in the machine shown this roller is also the wrapper carrier and presenting device.

Broadly considered and as independent of the cutting mechanism which has just been 10 described, the wrapper-presenting means may be widely varied in character, although it will be mounted in a suitable carrier with respect to which it rotates. As shown, the carrier for the wrapper-presenting means consists of a pair of arms 12 13, mounted on a 15 shaft 14, journaled in suitable bearings 15, secured to the frame. These arms serve to support a sleeve 16, which is journaled in the arms, and upon this sleeve is mounted the 20 wrapper-presenting means proper, which comprise in the present construction a perforated cylinder 17. The perforations in this cylinder are so arranged that as the roller rotates it will pick the leaf up from the perforated plate which lies inside the die, the perforations preferably taking the leaf close to the inner edge of the die, the suction created in the cylinder causing the leaf to adhere thereto.

25 30 The means for establishing the suction in the cylinder may be of any suitable character. As shown, the sleeve 16 is slotted at 18 and the arm 12 is formed with an air-passage therethrough, said passage being in communication with a pipe 19, which leads to a fan or other suitable suction-producing means.

It is apparent that by giving the carrier a suitable movement the cylinder 17 will be 35 caused to roll over the cutting-die and that a 40 wrapper will be cut from a leaf of tobacco or other sheet of material which has been previously laid upon the die, said wrapper being picked up and carried onward by the cylinder 17, it being of course understood that the 45 suction in the cylinder will be strong enough to take the wrapper away from the perforated bed of the die in case the suction is not cut off from the chamber beneath it, which may, however, be done.

50 55 The means for producing the movement of the carrier may be varied widely. As shown, the shaft 15 is provided with a segment 20, which is engaged by a segment - rack 21, formed on the arm 22 of a bell-crank lever 22 23, said lever being pivoted to the frame at 24. The arm 23 of the lever is or may be provided with a cam-roll 25, which engages with a cam-groove 26, formed in one of the faces of a cylinder 27, mounted on a cam-shaft 28. 60 The shaft 28 may be driven in any suitable manner. As shown, it is provided with a worm-gear 30, which is in engagement with a worm 31, mounted on the main driving-shaft 32, said shaft being shown as provided with a 65 driving-pulley 33.

In order to prevent any slip between the cylinder 17 and the die as the cylinder rolls

over the die, the cylinder will preferably be positively driven, the driving being effected by any suitable mechanism. As shown, the 70 sleeve 16, which carries the cylinder 17, is provided with a sprocket-wheel 34, over which passes a sprocket-chain 35, said chain also passing over a sprocket - wheel 36, loosely mounted on the shaft 15. Secured to this 75 sprocket-wheel 36 is a gear 37, said gear being driven by a segment-rack 38, formed on the arm 39 of a bell-crank lever 39 40, pivoted at 41 to the frame of the machine. The arm 40 of the bell-crank lever is or may be provided with a cam-roll 42, which engages with a cam 43, formed on the end of the cylinder 27, the bell-crank being held up to its duty by means of a spring 44.

After the cylinder 17 has passed over the 80 cutting-bed and cut and picked up a wrapper the movement of the carrier is continued to bring the cylinder into position to deliver the wrapper to a wrapping mechanism. The wrapping mechanism employed may be of any 85 suitable character, that illustrated being of the well-known Reuse type, the wrapping-jaws 45 being mounted on and driven by suitable shafts and gearing and the whole being mounted in a suitable frame 46. The main 90 driving-shaft for this wrapping mechanism is marked 47, said shaft being provided with a bevel-gear 48, which meshes with a similar gear 49, mounted on a vertical shaft, the other end of said shaft being provided with a 95 beveled gear 50, which meshes with a similar beveled gear 51, mounted on a counter-shaft 52. This counter-shaft is provided with a gear 53, which is in mesh with a gear 54, mounted on the main driving-shaft 32. The wrapping 100 mechanism illustrated is substantially the same as that illustrated and described in Patent No. 654,178, granted July 24, 1900, to R. L. Patterson and George Arents, Jr., as my assignees, and a fuller description herein is 105 unnecessary, as reference may be had to said patent for a full disclosure of the construction.

110 In cigar-wrapping machines it is desirable that a relative movement be produced between the wrapper-presenting means and the wrapping mechanism, which movement is the resultant of an approaching and traversing movement or an approaching, traversing, and angular movement for reasons fully set forth in Patent No. 654,178, granted July 24, 1900, to R. L. Patterson and George Arents, Jr. In the present machine provision is made for producing a relative movement between the wrapping mechanism and the wrapper-presenting means which is the resultant of the three movements referred to, although the 115 relative movement will vary, according to the shape of the article to be wrapped. In the present machine the wrapping mechanism is 120 given the angular movement, the frame 46 having secured to its under side a segment 55, which is engaged by a segment 56, formed on the arm 57, which is mounted on a vertical 125

shaft 58. The other end of this shaft carries an arm 59, which is or may be provided with a cam-roll 60, which engages with a cam-groove 61 in the cylinder 27. The approaching movement or the movement which delivers the wrapper is produced by rotating the wrapper-presenting cylinder 17 with respect to its carrier-arms, this rotation being effected by means of the sprocket-wheels 34 36, the chain 35, and the other driving connections before referred to, the cam 43 being of such a shape that it not only rotates the cylinder as it runs over the bed during the wrapper-cutting operation, but also rotates it during the wrapper-delivering operation. In the present machine the traversing movement is given to the wrapper-presenting means by mechanism which will now be described.

Referring to Fig. 2, it will be seen that there is located in the sleeve 16 a block 62, to which the cylinder 17 is connected by means of a pin 63, said pin passing through slots in the sleeve 16. Projecting from this block 62 is a stem 64, having on its outer end a grooved collar 65, which is engaged by a lever 66, pivoted at 67 to the carrier-arm 13, so as to move with said arm. The lower end of this lever 66 is provided with a pin which engages with a grooved collar 68, loosely supported on the shaft 14. This collar 68 is also engaged by a pin 69 on an arm 70, projecting from a short shaft 71, supported in a suitable bearing 72, secured to the frame of the machine. The other end of this shaft 71 carries an arm 73, which has on its inner end a cam-roll 74, which engages with a suitable cam-groove formed in the end of the cylinder 27. This groove is so shaped as to produce through the connections described a sliding movement of the cylinder 17 with respect to the sleeve upon which it is supported in the carrier-arms, this traversing movement being sufficient to cause the wrapper to be fed along the bunch in the wrapping mechanism.

It may be here remarked that under certain circumstances either the traversing or the angular movement, or both, might be omitted. It will also be understood that both traversing and angular movements might be given to the wrapping mechanism, if desired.

In delivering the wrapper it is desirable that that part of the circumference of the cylinder 17 which is delivering the wrapper stand directly opposite the opening in the wrapping mechanism in order that the lead of the wrapper between the cylinder and the wrapping mechanism may be as short as possible. When, however, the wrapping mechanism is given an angular movement, the swing of this mechanism would tend, were the wrapper-presenting cylinder stationary with respect to the wrapping mechanism, to move the mechanism away from that part of the cylinder which is delivering to the wrapper, thus increasing the length of the lead of the wrapper. To avoid this, means are preferably provided to produce a relative

compensating movement between the wrapping mechanism and the wrapper-presenting means. In the machine shown this is effected by moving the wrapper-presenting means.

Referring to the diagram, Fig. 5, in which the wrapper-presenting cylinder is shown as delivering the forward or tuck end of the wrapper to the bunch, and comparing the relative position of the wrapper-presenting cylinder in this figure with the positions illustrated in Figs. 6 and 7, which show the cylinder as delivering the wrapper to the center and tip ends of the bunch, respectively, it will be noted that the cylinder has moved back somewhat from the extreme forward position illustrated in Fig. 5. This backward movement is effected through the carrier-operating means, the cam 26 being properly shaped and timed to produce this backward or compensating movement during the wrapper-delivering operation.

Means are preferably provided to insure the positive presentation of the leading or tuck end of the wrapper to the bunch. While these means may be varied in character, a blast mechanism will be preferably employed for this purpose. In the construction shown the sleeve 16 is provided with a recessed block 75, which is shown as integral with the sleeve, the recess in said block communicating with those perforations which underlie the forward or tuck end of the wrapper when it is positioned on the cylinder 17. Communicating with the recess in the block 75 is a blast-pipe 76, said pipe being led through the sleeve 16 and the carrier-arm 12 and down alongside the carrier-arm. The lower end of this pipe 76 is given an angular bend, as indicated at 77, and is arranged to come into register with a blast-nozzle 78, suitably mounted in a bracket 79, extending from the frame of the machine, said nozzle being in communication with any suitable blast-producing mechanism—such, for instance, as a fan. The parts are so arranged that the angular bend on the pipe 76 and the nozzle come into register at the precise time when the tuck end of the wrapper is positioned over and is to be delivered to the tuck end of the bunch.

It will be understood that changes and variations may be made in the construction by which the invention is carried into effect. It will further be understood that certain parts of the construction in which the invention is embodied may be used independently of other parts. The invention is not, therefore, to be limited to the precise constructions and combinations hereinbefore described.

What is claimed is—

1. The combination with a wrapping mechanism, of a wrapper-presenting means, a carrier therefor in which said means is mounted to rotate, means for moving the carrier to bring the wrapper-presenting means into delivery position, and means for rotating said presenting means on the carrier to deliver the wrapper, substantially as described.

2. The combination with a wrapping mechanism, of a perforated wrapper-supporting cylinder, means for establishing suction in the cylinder, a carrier for the cylinder, means for moving the carrier to bring the cylinder into delivery position, and means for rotating the cylinder to deliver the wrapper, substantially as described. 5

3. The combination with a wrapping mechanism, of a wrapper-presenting means, a carrier therefor in which said means is mounted to rotate, means for moving the carrier to bring the presenting means into delivery position, means for giving the presenting means a rotating movement on the carrier to deliver the wrapper, and means for producing a relative traversing movement between the wrapping mechanism and the presenting means, substantially as described. 10

4. The combination with a wrapping mechanism, of a wrapper-presenting means, a carrier therefor in which said means is mounted to rotate, means for moving the carrier to bring the presenting means into delivery position, means for giving the presenting means a rotating movement on the carrier to deliver the wrapper, and means for producing a relative angular movement between the wrapping mechanism and the presenting means, substantially as described. 15

5. The combination with a wrapping mechanism, of a wrapper-presenting means, a carrier therefor in which said means is mounted to rotate, means for moving the carrier to bring the presenting means into delivery position, means for giving the presenting means a rotating movement on the carrier to deliver the wrapper, and means for producing a relative angular movement and a relative traversing movement between the wrapping mechanism and the presenting means during the delivery of the wrapper, substantially as described. 20

6. The combination with a wrapping mechanism, of a wrapper-presenting means, a carrier therefor in which said means is mounted to rotate, means for moving the carrier to bring the presenting means into delivery position, means for giving the presenting means a rotating movement on the carrier to deliver the wrapper, and means for giving the presenting means a traversing movement during the delivery of the wrapper, substantially as described. 25

7. The combination with a wrapping mechanism, of a wrapper-presenting means, a carrier therefor in which said means is mounted to rotate, means for moving the carrier to bring the presenting means into delivery position, means for giving the presenting means a rotating movement on the carrier to deliver the wrapper, means for giving the presenting means a traversing movement during the delivery of the wrapper, and means for giving the wrapping mechanism an angular movement, substantially as described. 30

8. The combination with a wrapping mech- 35

anism, of a perforated wrapper-supporting cylinder, means for establishing suction in the cylinder, a carrier for the cylinder, means for moving the carrier to bring the cylinder into delivery position, means for giving the cylinder a rotating movement on the carrier to deliver the wrapper, and means for producing a relative traversing movement between the wrapping mechanism and the cylinder, substantially as described. 40

9. The combination with a wrapping mechanism, of a perforated wrapper-supporting cylinder, means for establishing suction in the cylinder, a carrier for the cylinder, means for moving the carrier to bring the cylinder into delivery position, means for giving the cylinder a rotating movement on the carrier to deliver the wrapper, and means for producing a relative angular movement between the wrapping mechanism and the cylinder, substantially as described. 45

10. The combination with a wrapping mechanism, of a perforated wrapper-supporting cylinder, means for establishing suction in the cylinder, a carrier for the cylinder, means for moving the carrier to bring the cylinder into delivery position, means for giving the cylinder a rotating movement on the carrier to deliver the wrapper, and means for producing a relative angular movement and a relative traversing movement between the wrapping mechanism and the cylinder during the delivery of the wrapper, substantially as described. 50

11. The combination with a wrapping mechanism, of a perforated wrapper-supporting cylinder, means for establishing suction in the cylinder, a carrier for the cylinder, means for moving the carrier to bring the cylinder into delivery position, means for giving the cylinder a rotating movement on the carrier to deliver the wrapper, and means for giving the cylinder a traversing movement during the delivery of the wrapper, substantially as described. 55

12. The combination with a wrapping mechanism, of a perforated wrapper-supporting cylinder, means for establishing suction in the cylinder, a carrier for the cylinder, means for moving the carrier to bring the cylinder into delivery position, means for giving the cylinder a rotating movement on the carrier to deliver the wrapper, means for giving the cylinder a traversing movement during the delivery of the wrapper, and means for giving the wrapping mechanism an angular movement, substantially as described. 60

13. The combination with a wrapping mechanism, of a wrapper-presenting means, a carrier in which said means is mounted to rotate, means for moving the carrier to bring the presenting means into delivery position, means for rotating the presenting means on the carrier, means for producing a relative angular movement between the presenting means and the wrapping mechanism during the delivery of the wrapper, and means for 65

producing a compensating movement between the presenting means and the wrapping mechanism, substantially as described.

14. The combination with a wrapping mech-

5 anism, of a wrapper-presenting means, a carrier in which said means is mounted to rotate, means for moving the carrier to bring the presenting means into delivery position, means for rotating the presenting means on the carrier, means for giving the wrapping mechanism an angular movement during the delivery of the wrapper, and means for giving the wrapper-presenting means a compensating movement, substantially as described.

15. The combination with a wrapping mech-
5 anism, of a wrapper-presenting means, a carrier in which said means is mounted to rotate, means for moving the carrier to bring the presenting means into delivery position, means for rotating the presenting means on the carrier, means for giving the wrapping mechanism an angular movement during the delivery of the wrapper, means for giving the wrapper-presenting means a traversing move-
25 ment, and means for giving said presenting means a compensating movement, substantially as described.

16. The combination with a wrapping mech-
5 anism, of a perforated wrapper-supporting cylinder, means for establishing suction in the cylinder, a carrier in which said cylinder is mounted to rotate, means for moving the carrier to bring the cylinder into delivery position, means for rotating the cylinder on the carrier, means for producing a relative angular movement between the cylinder and the wrapping mechanism during the delivery of the wrapper, and means for producing a compensating movement between the cylinder and the wrapping mechanism, substan-
40 tially as described.

17. The combination with a wrapping mech-
5 anism, of a perforated wrapper-supporting cylinder, means for establishing suction in the cylinder, a carrier in which said cylinder is mounted to rotate, means for moving the carrier to bring the cylinder into delivery position, means for rotating the cylinder on the carrier, means for giving the wrapping mech-
45 anism an angular movement during the de-
livery of the wrapper, and means for giving the supporting-cylinder a compensating movement, substantially as described.

18. The combination with a wrapping mech-
55 anism, of a perforated wrapper-supporting cylinder, means for establishing suction in the cylinder, a carrier in which said cylinder is mounted to rotate, means for moving the carrier to bring the cylinder into delivery position, means for rotating the cylinder on the carrier, means for giving the wrapping mechanism an angular movement during the delivery of the wrapper, means for giving the supporting-cylinder a traversing movement,
60 and means for giving said cylinder a compen-
65 sating movement, substantially as described.

19. The combination with a cutting-bed, of means for holding a sheet of material thereon, a coöperating cutting member, means for pro-
70 ducing a relative cutting movement between said members, and means for transferring the cut portion of the sheet from the bed to the coöperating cutting member, substan-
75 tially as described.

20. The combination with a cutting-bed, of means for holding a sheet of material thereon, a coöperating perforated cylinder, means for establishing suction in the cylinder where-
80 by the cut portion of the sheet is transferred from the bed to the cylinder, and means for producing a relative cutting movement be-
tween the bed and the cylinder, substantially as described.

21. The combination with a cutting-bed, of means for holding a sheet of material thereon, a coöperating perforated cylinder, means for establishing suction in the cylinder where-
85 by the cut portion of the sheet is transferred from the bed to the cylinder, and means for moving the cylinder over the bed, substan-
90 tially as described.

22. The combination with a wrapping mech-
95 anism, of a cutting-bed, means for holding a sheet of material thereon, a combined cutting member and wrapper-support, means for pro-
ducing a relative cutting movement between the bed and said support, means for trans-
ferring the cut portion of the sheet from the bed to the support, and means for producing 100 a relative delivery movement between the support and the wrapping mechanism, sub-
stantially as described.

23. The combination with a wrapping mech-
105 anism, of a cutting-bed, means for holding a sheet of material thereon, a perforated cylin-
der operating as a cutting member and a wrap-
110 per-support, means for creating suction in the cylinder whereby the cut portion of the sheet is transferred from the bed to the cylinder, means for producing a relative cut-
ting movement between the bed and the cyl-
115 inder, and means for producing a relative delivery movement between the wrapping mechanism and the cylinder, substantially as described.

24. The combination with a wrapping mech-
120 anism, of a cutting-bed, means for holding a sheet of material thereon, a perforated cylin-
der operating as a cutting member and a wrap-
125 per-support, means for creating suction in the cylinder, means for moving the cylinder over the bed to cut a wrapper and pick it up from the bed, and means whereby the cylinder is caused to deliver the wrapper to the wrapping mechanism, substantially as described.

25. The combination with a cutting-bed, of means for holding material thereon, a perforated coöperating cylinder, means for creat-
130 ing suction therein, means for producing a relative cutting movement between the bed and the cylinder, whereby a portion of the sheet is cut out and transferred to the cylinder, and means for positively driving the cyl-

inder during the cutting movement, substantially as described.

26. The combination with a cutting-bed, of means for holding a sheet of material thereon, a coöperating perforated cylinder, means for creating suction therein, means for moving the cylinder over the bed to cut and take up a portion of the material therefrom, and means for positively driving the cylinder as it moves across the bed, substantially as described.

27. The combination with a wrapping mechanism, of a cutting-bed, means for holding material thereon, a perforated coöperating cylinder, means for creating suction therein, means for producing a relative cutting movement between the bed and the cylinder whereby a portion of the material is cut out and transferred to the cylinder, and means for positively driving the cylinder during the cutting movement, substantially as described.

28. The combination with a wrapping mechanism, of a cutting-bed, means for holding material thereon, a coöperating perforated cylinder, means for creating suction therein, means for moving the cylinder over the bed to cut and take up a portion of the material therefrom, and means for positively driving the cylinder as it moves across the bed, substantially as described.

29. The combination with a wrapping mechanism, of a cutting-bed, means for holding material thereon, a coöperating perforated cylinder, means for creating suction therein, means for producing a relative cutting movement between the bed and the cylinder whereby a portion of the material is cut out and transferred to the cylinder, means for positively driving the cylinder during the cutting movement, and means whereby the cylinder delivers the cut-out portion of the material to the wrapping mechanism, substantially as described.

30. The combination with a perforated cylindrical support for sheet material, of connections whereby the air may be exhausted from the interior of the support, and connections whereby a blast may be caused to pass into the interior of the support, substantially as described.

31. The combination with a perforated cylindrical support for sheet material, of connections whereby the air may be exhausted from the interior of the support, and connections whereby a blast may be caused to pass into the interior of the support, said blast connections registering with a portion only of the perforations of the support, substantially as described.

32. The combination with a perforated cylindrical support for sheet material, of connections whereby the air may be exhausted from the interior of said support, and connections whereby a blast may be introduced into

33. The combination with a perforated support and registers with only a part of the perforations therein, substantially as described.

33. The combination with a perforated cylinder which forms a support for sheet material, of connections whereby the air may be exhausted from the interior of the cylinder, a part connected to the cylinder and registering with only a part of the perforations therein, and a stationary blast-pipe communicating with said part, substantially as described.

34. The combination with a perforated cylinder, of means for supporting and rotating the same, means for exhausting the air from the interior of the cylinder, a recessed block registering with a part of the perforations of the cylinder, and a stationary blast-pipe communicating with said block, substantially as described.

35. The combination with a perforated cylinder, of means for supporting, rotating and giving the cylinder a movement in the direction of its axis of rotation, means for exhausting the air from the interior of the cylinder, a recessed block registering with a part of the perforations of the cylinder, and a stationary blast-pipe communicating with said block, substantially as described.

36. The combination with a wrapping mechanism, of a perforated cylinder, a pair of arms, a sleeve in communication with the cylinder and supported by the arms, means for rotating the cylinder, means for exhausting the air from the sleeve and cylinder, a recessed block in communication with a part of the perforations of the cylinder, and a blast-pipe communicating with said recessed block, substantially as described.

37. The combination with a wrapping mechanism, of a pair of supporting-arms, a sleeve mounted thereon, a perforated cylinder carried on the sleeve, means for rotating the cylinder, means for exhausting the air therefrom, means whereby a blast may be caused to pass through a part of the perforations of the cylinder, and means for giving the cylinder a movement in the direction of its axis, substantially as described.

38. The combination with a wrapping mechanism, of a pair of supporting-arms, a sleeve supported in the arms, a perforated cylindrical wrapper-support mounted on the sleeve, means for operating the arms to bring the support into delivery position with respect to the wrapping mechanism, means for exhausting air from the support, a blast-pipe passing through the sleeve, a connection between the blast-pipe and a part of the perforations of the cylinder, means for rotating the support to cause it to deliver the wrapper, and means for giving the support a movement in the direction of its axis of rotation during the wrapper-delivering operation, substantially as described.

39. The combination with a wrapping mechanism, of means for giving it an angular move-

ment, a pair of supporting - arms, a hollow sleeve carried by the arms, a perforated cylinder the interior of which is in communication with the sleeve, connections whereby the air may be exhausted from the sleeve, a blast-pipe passing through the sleeve, a recessed block secured to the interior of the cylinder and communicating with the blast-pipe, the recess in said block registering with some of the perforations in the cylinder, means for moving the cylinder lengthwise of the sleeve, means for operating the arms to bring the cylinder into delivery position with respect to the wrapping mechanism and for giving it a compensating movement during the wrapping operation, and means for rotating the cylinder to cause it to deliver the wrapper to the wrapping mechanism, substantially as described.

40. The combination with a wrapping mechanism, of means for giving it an angular movement, a perforated cutting-bed on which a sheet of wrapper material is held by suction, a perforated cylinder, a pair of supporting-arms, means for supporting the cylinder in said arms, means for exhausting the air from the interior of the cylinder, means whereby the arms are operated to cause the cylinder to roll over the cutting-bed to cut out a wrapper and pick up and bring said wrapper into delivery position and to give said cylinder a compensating movement during the wrapping operation, means for rotating the cylinder to deliver the wrapper, means for giving it a lengthwise movement, and a blast-pipe and suitable connections for forcing the tip of the wrapper away from the cylinder and into the wrapping mechanism, substantially as described.

41. The combination with a cutting-die, of a coöperating cutting member, and means for pivotally supporting said die to allow it to tilt under the pressure of the coöperating member, whereby inequalities are compensated for, substantially as described.

42. The combination with a cutting-die, of a coöperating cutting-roller, means for pivotally supporting said die to allow it to tilt under the pressure of the coöperating roller, whereby inequalities are compensated for, and means for producing a relative cutting movement between the die and the roller, substantially as described.

43. The combination with a cutting-die, of a perforated coöperating cutting-roller, means for pivotally supporting said die to allow it to tilt under the pressure of the coöperating roller, whereby inequalities are compensated for, and means for producing a relative cutting movement between the die and the roller, substantially as described.

44. The combination with a cutting-die, of a coöperating cutting member, the base of said die being shaped to provide a bearer of less area than the base, whereby the die is permitted to tilt under the pressure of the coöperating cutting member in order to compensate for inequalities, substantially as described.

45. The combination with a cutting-die, of a coöperating cutting-roller, the base of said die being shaped to provide a bearer of less area than the base, whereby the die is permitted to tilt under the pressure of the coöperating cutting-roller in order to compensate for inequalities, and means for producing a relative cutting movement between the die and the roller, substantially as described.

46. The combination with a cutting-die, of a coöperating perforated cutting-roller, the base of said die being shaped to provide a bearer of less area than the base, whereby the die is permitted to tilt under the pressure of the coöperating cutting-roller in order to compensate for inequalities, and means for producing a relative cutting movement between the die and the roller, substantially as described.

47. The combination with a cutting-die, of a coöperating cutting member, the base of the die being shaped to provide a knife-edge bearing on which the die is permitted to tilt under the pressure of the coöperating cutting member to compensate for inequalities, substantially as described.

48. The combination with a cutting-die, of a coöperating cutting-roller, the base of the die being shaped to provide a knife-edge bearing on which the die is permitted to tilt under the pressure of the coöperating cutting-roller to compensate for inequalities, and means for producing a relative cutting movement between the die and the roller, substantially as described.

49. The combination with a cutting-die, of a coöperating perforated cutting-roller, the base of the die being shaped to provide a knife-edge bearing on which the die is permitted to tilt under the pressure of the coöperating cutting-roller to compensate for inequalities, and means for producing a relative movement between the die and the roller, substantially as described.

In testimony whereof I have hereunto set my hand in the presence of two subscribing witnesses.

OLUF TYBERG.

Witnesses:

ROBT. G. GRUNERT,
SYDNEY IRVIN PRESCOTT.
